US0D1087176S

(12) **United States Design Patent** (10) **Patent No.:** **US D1,087,176 S**
(45) **Date of Patent:** **** Aug. 5, 2025**

(54) **WINCH**

- (71) Applicant: **Tractor Supply Co. of Texas, LP**, Brentwood, TN (US)
- (72) Inventors: **Christian D. Fogg**, Columbia, TN (US); **Jace A. McDill**, Nashville, TN (US); **Zhilin Yu**, Zhejiang Province (CN)
- (73) Assignee: **Tractor Supply Co. of Texas, LP**, Brentwood, TN (US)
- (**) Term: **15 Years**

(21) Appl. No.: **29/920,869**

(22) Filed: **Dec. 13, 2023**

(51) LOC (15) Cl. **12-05**
(52) U.S. Cl. **D34/33**

(57) **CLAIM**

The ornamental design for a winch as shown and described.

DESCRIPTION

FIG. 1 is a front top left perspective view showing the winch.

FIG. 2 is a front top right perspective view showing the winch

FIG. 3 is another front top left perspective view at a different viewing angle than FIG. 1, showing the winch.

FIG. 4 is another front top right perspective view at a different viewing angle than FIG. 2, showing the winch.

FIG. 5 is a rear top left perspective view showing the winch.

FIG. 6 is a rear bottom right perspective view showing the winch.

FIG. 7 is a rear bottom left perspective view showing the winch.

FIG. 8 is a front view showing the winch.

FIG. 9 is a rear view showing the winch.

FIG. 10 is a top view showing the winch.

FIG. 11 is a bottom view showing the winch.

FIG. 12 is a left end view showing the winch; and,

FIG. 13 is a right end view showing the winch.

1 Claim, 11 Drawing Sheets
